(57) **CLAIM**

The ornamental design for a surge protector, as shown and described.

DESCRIPTION

FIG. 1 is a front perspective view of a surge protector, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of its expanded state.

The broken lines in the drawings illustrate the portions of the surge protector, which form no part of the claimed design.
